[57] CLAIM

The ornamental design for a embossed panel for magazine holder, as shown and described.

DESCRIPTION

FIG. 1 is a front perspective view from the right side of my embossed panel for magazine holder;

FIG. 2 is a front elevational view thereof;

FIG. 3 is a right side elevation view thereof, with the left elevational view being the mirror image thereof;

FIG. 4 is a top view thereof; and,

FIG. 5 is a cross-sectional view taken along line 5—5 of FIG. 2.

The remainder of the magazine holder structure depicted by means of broken lines in FIG. 1 has been shown for illustrative purposes only and forms no part of the claimed design.
